GUIDE FOR STRIP MILLS OR THE LIKE

Edward Brangle, Newburg Heights, and Vincent
Kolasinski, Cleveland, Ohio

Application February 24, 1938, Serial No. 192,404

1 Claim. (Cl. 80—51)

Our invention relates to a mill bar guide for use in a steel strip mill, and particularly to a guide of this type having a wearing element involving a plurality of usable wearing surfaces which are presentable by adjustment of the wearing element, and an important object of my invention is to provide a guide of the character indicated which is considerably cheaper and lasts longer in service before requiring replacement.

Other important objects of our invention will be apparent from a reading of the following description taken in connection with the drawing, wherein for purposes of illustration we have shown a preferred embodiment of our invention.

In the drawing:

Figure 1 is a perspective view of the guide body constructed in accordance with the present invention.

Figure 2 is a perspective view of the replaceable wearing element.

Figure 3 is a transverse vertical sectional view of the invention.

While not necessarily confined to use and in corporation with a 30-inch "four high cold strip mill," the invention may be well illustrated by description thereof in connection with such a strip mill, since the invention in use in such a strip mill may be used at least eight times under standard conditions by changing the wearing element's exposed surface, whereas under standard conditions the present guides can usually be used only four times at best and with considerable difficulty, whereas the present invention may be used at least eight times with the greatest of convenience. This fact represents a saving of at least 50 percent as far as the use of material is concerned.

As a further illustration of the economical character of the present invention it is pointed out that for a machine of the type indicated the presently used guides involve a wearing element containing approximately 28.81 cubic inches of material, whereas the wearing element of the presently disclosed guide contains approximately 19.05 cubic inches, being a difference of 9.76 cubic inches so that it is evident a 34 percent saving in the quantity of material required is produced. This 34 percent saving in material and the capability of the use of the guide eight times instead of four, represents a total approximate saving in the cost of guides for the type of machine indicated of from 75 to 84 percent, particularly on a No. 30' 4 high cold strip mill.

Referring in detail to the drawing, the numeral 5 generally designates the body of the strip guide which is preferably formed of adequately hard material such as steel in an elongated rectangular form provided in one side with a seat or channel 6 which is bounded at its ends by respective shoulders 7 and 8. The channel defines upper and lower walls 9 and 10 and a web or outer wall 11. This outer wall is provided at suitable intervals with holes 12, 13 to facilitate removal of the wearing element which is generally designated 14 and which is held in place in the channel by means of flat headed set screws 16 working in appropriate openings 15 in the top wall 9 of the guide body. The left hand end of the guide body has a solid portion 17 which is generally rectangular in cross section except for the cut-off corner 18 and the relatively small cut away portion 19 forming the inner face of the shoulder 7. At the opposite end of the body 5 the upper and lower corners thereof are cut away at an angle as indicated by the numerals 20 and 21 and a cut away portion 22 bounds the inner face of the shoulder 8 as clearly illustrated in the drawing.

The wearing element generally designated 14 is of the same material as presently used, such as brass, and substantially perfectly square in cross section and of an exact length to fit in the channel 6 of the body or guide box 5 without any tolerance or clearance, and to be locked in place in the said channel by proper adjustment of the set screws 16. By application of a suitable tool through the openings 12 and 13 in the guide box the wearing element 14 may be removed when the exposed surface has become worn down and the wearing element 14 may then be replaced in the channel with another one of its four surfaces exposed for further utilization of the guide. As indicated in Figure 3 of the drawing, an unworn surface of the wearing element 14 will project from the channel 6 flush with the inner face of the guide box.

As in the case of the wearing element 14, the channel 6 has no tolerance whatsoever in length, width, depth or thickness, and for a No. 11 mill, the guide box will be 33 $\frac{1}{2}$ inches wide and the widest stock run on the No. 11 mill is 27 inches wide. The wearing element 14 will be exactly 1 $\frac{1}{8}$ inches thick and 15 inches long on all four sides. It will be understood, of course, that different dimensions will be called for by the dimensions of the different machines with which the guide is to be used. It will also be under-

stood that guides for the opposite side of the 5
guide box of the mill will simply have their
arrangements exactly reversed with respect to
those described herein, a pair of the guides
usually being used to guide the opposite sides
of the steel strip as it is fed through the guide
box toward the roll in the cold roll strip mill.

In the arrangements presently in use, for the
size of machine indicated, it is necessary to buy
10 or pay for a greater number of pounds of brass
and then have only one wearing surface whereas
in accordance with the present invention, the
wearing element requires an expenditure for a
15 smaller number of pounds of brass and it at the
same time provides four instead of one wearing
surface.

Although we have shown and described herein
a preferred embodiment of our invention, it is
20 to be definitely understood that we do not desire
to limit the application of the invention thereto,
and any change or changes may be made in the
materials and in the structure and arrangement
of the parts, within the spirit of the invention
and the scope of the subjoined claim.

25 Having described the invention, what is
claimed as new is:

A guide for a strip mill comprising an elongated
body formed of one piece of material and

having one side edge straight and formed with
a channel which extends from one end of the
body through the other end thereof, the end portions
of the channel being of less depth than
the major portion thereof to provide abutment
shoulders at the ends of the said major portion,
the said major portion being of uniform width
and depth with the upper and lower walls flat
and parallel to each other and the inner wall
being flat and arranged at right angles to the 10
upper and lower walls and all three walls being
of the same width, a wear bar of square shape
in cross section and of a width and thickness
to snugly fit in the major portion of the channel
with its ends contacting the abutment shoulders 15
and three of its side walls contacting the three
walls of the channel, the fourth side wall being
flush with said straight edge of the body, the top
of the body having countersunk holes screw passing
therethrough and through the top wall of 20
of the channel, screws fitting in the holes and
engaging the bar for removably holding said bar
in the channel and plain holes passing from the
inner wall of the channel through the opposite
wall of the body for the introduction of a member 25
to push the bar from the channel.

EDWARD BRANGLE.
VINCENT KOLASINSKI.
